PNEUMATIC TIRE

Marcia G. Mylor, Detroit, Mich., assignor to United States Rubber Company, New York, N. Y., a corporation of New Jersey

Application March 22, 1954, Serial No. 29,631

Term of patent 14 years

(Cl. D90—20)

Fig. 1

Fig. 2

Fig. 1 is a side elevational view of a pneumatic tire embodying my new design; and

Fig. 2 is an enlarged sectional and fragmentary perspective view taken on line II-II of Fig. 1.

My design for the pneumatic tire shown is characterized by the configuration and appearance of the side wall thereof which comprises three annular concentric side wall zones between the tire bead and tire tread; the inner boundaries of the two outer zones being defined by downwardly stepped inwardly facing shoulders, and the two outer zones being of relatively dark color and the inner zone being white.

I claim:

The ornamental design for a pneumatic tire, substantially as shown and described.
